UNITED STATES PATENT OFFICE.

OTTO C. WINESTOCK, OF PERKINSVILLE, VERMONT.

METHOD FOR WASHING PULP.

Application filed September 17, 1917, Serial No. 191,842. Renewed July 26, 1923.

To all whom it may concern:

Be it known that I, Otto C. WINESTOCK, a citizen of the United States, and a resident of Perkinsville, in the county of Windsor and State of Vermont, have invented certain new and useful Improvements in Methods for Washing Pulp, of which the following is a specification.

This invention relates broadly to washing apparatus, and more specifically to a pulp washing device adapted particularly for the use of paper manufacturers in rendering used or inked paper suitable for re-use.

The principal object of the present invention is to provide an improved method and apparatus for washing pulp, which apparatus may be operated continuously, the waste or dirty water used in washing being gradually thrown off so that it is not ground into the paper fibers.

A further object of the present invention is to provide a washing apparatus comprising a series of tubular washers through which the pulp is continuously passed, and so constructing the same that a considerable quantity of water may be kept therein to assist in the agitating, washing and flowing of the pulp.

Still another object of the present invention is to provide a series of tubes of the above nature having therein means for continuously agitating, washing and feeding the pulp.

A still further object of the present invention is to provide in such a washer means for regulating the amount of pulp contained therein.

These and other objects, together with their attendant advantages will be apparent as the invention becomes better understood by reference to the accompanying specification, and drawings forming a part thereof, throughout the several views of which like characters of reference have been used to indicate like parts.

In the drawings, Figure 1 is a side view of my improved washing apparatus.

Figure 2 is a cross sectional view illustrating the relative positions of the tubular washers.

Figure 3 is a detail view showing the adjustable dam or gate for regulating the quantity of pulp in the washer.

Figure 4 is an enlarged view of a modified form of washer.

Figure 5 is a detail view of an adjustable

mounting for the agitating or propelling blades.

With machines and processes heretofore employed for washing paper pulp it has 60 been difficult to obtain a washed pulp suitable for many uses for the reason that the ink and the like loosened from the used pulp has been ground or beat back into the fibers by the action of the washer. This results in 65 a discoloration of the fibers which renders them objectionable for many purposes. With the present invention this objection is almost entirely eliminated inasmuch as the waste water is thrown off as it becomes dirty 70 so that the fibers are continually subjected to the action of clean washing fluid.

Referring more particularly to the drawings, my improved washer preferably comprises a plurality of tubular members 1 which may be of any desired length depending upon the type of pulp to be washed, and the number of which may be varied at will depending upon the particular use of the machine. Each of the tubes preferably comprises an imperforate lower portion 2 in the form of a half tube, and an upper perforate portion 4 secured to the imperforate portion by means of the flanges 5 formed thereon, and the co-operating locking plates 6. The 80 perforate portion of the tube may be constructed of ordinary heavy screening, or of sheet metal having a plurality of openings suitably punched therethrough. In order to construct the apparatus so that the 85 smallest possible amount of room is utilized in installing the same, the tubes are preferably constructed in comparatively short sections which may be connected by elbows 7 so that they occupy the desired positions. 90 While the elbows are indicated as being of solid material throughout, they may be constructed with a perforate portion in the same manner as the main body of the tubes in case such a construction is deemed advisable. The pulp to be washed is fed to a chest 8 having the usual overflow connection, and in communication with the tubes through a regulating valve 9 of any desired construction.

Extending longitudinally of the tubes, and projecting beyond the connecting elbows is a plurality of hollow shafts 10 journaled in suitable stuffing boxes 11 secured to the elbows. The shafts are adapted to be rotated by means of gears or the like 12 splined thereto in any well known manner, and

UNITED STATES PATENT OFFICE.

WILEM YUSKIEWICZ, OF BROCKTON, PENNSYLVANIA.

ASH SIFTER.

Application filed December 19, 1922. Serial No. 607,801.

To all whom it may concern:

Be it known that I, WILEM YUSKIEWICZ, a citizen of Poland, residing at Brockton, in the county of Schuylkill and State of Pennsylvania, have invented certain new and useful Improvements in Ash Sifters, of which the following is a specification.

This invention relates to new and useful improvements in ash sifters.

10 An important object of the invention is to provide an ash sifter of the enclosed type that is adapted for separating the ash dust from the unburnt coals and depositing the same into separate receptacles.

15 A further object of the invention is to provide an automatic feeding means for regulating the amount of ashes fed to the sifting member and wherein the feeding means and sifting member are actuated in unison to 20 prevent overloading of the said sifting member.

A further object of the invention is to provide a means for varying the position of the sifting member to regulate the passage of the unburnt coals thereover.

Other objects and advantages of the invention will be apparent during the course of the following description.

In the accompanying drawings forming 30 a part of this specification and in which like numerals are employed to designate like parts throughout the same,

Fig. 1 is a side elevational view of the invention,

35 Fig. 2 is a top plan view, having the top removed to show the ash receiving hopper,

Fig. 3 is a vertical sectional view taken on line III—III of Fig. 2, and shows the dust receiving receptacle and unburnt coal receiving receptacle partly in elevation and partly in section,

Fig. 4 is a horizontal sectional view taken on line IV—IV of Fig. 3, and

40 Fig. 5 is a detailed view of the regulating means used for feeding the ashes from the ash receiving hopper to the sifting member.

In the drawings, wherein for the purpose of illustration is shown a preferred embodiment of my invention, the numeral 1 designates a casing having side walls 2 and 3, end walls 4 and 5, bottom wall 6 and open top 7, the casing is further provided with legs 8 that are positioned at the four corners of the bottom 6, and handles 9 that are carried by the opposite side walls to furnish means for carrying the ash sifter

from place to place as desired. The side wall 2 is provided with a door 10 that is secured to the said wall by means of the hinges 11 and is further provided with a catch 12 for retaining the door in a closed position. The end wall 4 is provided with a door 13 that is hingedly connected to the casing by the hinges 14 and is further provided with a catch member 15 for retaining the door in a closed position. The open top 7 is provided with a cover 16 that is connected to the casing by means of the hinges 17 and is further provided with a handle knob 18 to facilitate the opening of the same when ashes are to be placed within the casing.

Referring more particularly to Figures 2 and 3 there is shown an ash-receiving hopper member 19 that is formed integrally with the said casing and having walls that slope towards the opening 20 formed by the lower edges thereof. The passage of ashes through the opening 20 is controlled by the flap valve 21 having a supporting rod 22 that is pivotally secured to the under face of the hopper member by the eye-bolts 23. The said flap valve is normally held in a closed position by means of a spring member that consists of the valve engaging portion 24 having its ends coiled around the supporting rod 22 as at 25 to terminate in resilient arms 26 that are adapted to press against the under surface of the hopper member for retaining the supporting portion 24 against the under surface of the flap valve 21. This flap valve is further provided with a wire member 27 that is secured to the supporting rod 22 and extends transversely to be bent around the supporting portion 24 to form a depending arm 28 having an eye 29 that is formed thereon to provide a connection for actuating mechanism that will be presently described.

The sifting member, as best shown in Fig. 3, embodies a rectangular frame consisting of side walls 30 and one end wall 31, the opposite end being left open for discharging the unburnt coals from the same after the ash dust has been separated therefrom. The bottom of the sifting member consists of a transverse end board 32 that is secured to the lower edges at the open end of the side walls 30 and adapted for strengthening the same, and is provided with a depending deflector plate 33 that is adapted to direct the coal dust, passing through the wire sifting

screen 34, into the receptacle 35 placed therebelow. The forward end of the sifting member is supported by the angular rod 36 that is pivotally secured as at 37 to the side walls of the casing, and to the end board 32 by the straps 38. The inner end of the sifting member is vertically adjustably supported by means of the longitudinally extending arms 39 that are secured to the side walls 30 as at 40 and have flexible cords 41, that are secured to the outer ends of the arms 39 and extend upwardly to be wound around the sheaves 42 that are carried by the horizontal shaft 43. This shaft 43 is journaled at one end within the bearing member 44, carried by the side wall 3, and at its opposite end is journaled in the bearing member 45 carried by the side wall 2 and projects outwardly therefrom for carrying the ratchet wheel 46 and operating wheel 47. A spring pressed pawl 48 is carried by the side wall 2 and is adapted to engage the teeth of the ratchet wheel to retain the sifting member in its adjusted position. Positioned beneath the open end of the sifting member are deflector plates 49 that are provided to direct the unburnt coals into the receptacle 50 positioned therebelow. It is to be understood that the receptacle 50 may be removed from the casing through the door 10 carried by the side wall 2 and that the receptacle 35 may be removed from the casing through the door 13 carried by the end wall 4. These two receptacles are further provided with finger gripping apertures 51 to facilitate in removing the same from the casing. The bottom wall 6 is provided with an upwardly directed flange 52 which acts as a partition between the two receptacles.

The actuating means for the sifting member and the flap valve 21 embodies a relatively large gear 52 that is carried by the shaft 53 that is journaled in the opposite sides of the casing 1 and provided with an operating crank handle 54 as shown in Figures 1 and 2. Secured to the laterally extending lugs 55 and journaled therein, is a crank shaft 56 that carries the pinion 57 secured thereto, which is constantly in mesh with the larger gear 52. A crank portion 58 is formed on the crank shaft 56 and is loosely connected to the substantially V-shaped member 59 that extends forwardly to be connected to the side walls 30 of the sifting member by the transverse rod 60. A connection rod 61 is journaled upon the transverse rod 60 as at 62 and is connected at its free end to the eye 29 carried by the depending arm 28 that is associated with the flap valve 21.

The operation of the device is as follows: Unsifted ashes are placed within the hopper member 19 through the opening 7 of

the casing and the cover 16 is moved to close the opening to prevent ash dust from leaving the hopper. The sifting member is adjusted to its proper inclined position by the operating wheel 47 to regulate the speed of travel of the ashes over the sifting screen 34. The crank handle 54 is operated to rotate the gear 52 to rotate the crank shaft 56 through the medium of the pinion 57, the crank portion 58, being connected with the sifting member through the substantially V-shaped member 59, will cause the said sifting member to reciprocate, from its full line position to its dotted line position as shown in Fig. 3, upon its forward supporting angular rod 36 and rear end supporting cords 41 to cause the ash dust to be sifted through the screen 34 into the receptacle 35 and to feed the unburnt coals forwardly to the open end of the member into the said receptacle 50. The connection rod 61, being connected to the sifting member by the horizontal rod 60, will actuate the flap valve 21 in unison with the sifting member, to cause a charge of unsifted ashes to be deposited from the hopper member 19 into the inner end of the sifting member.

It will be apparent that regulating the feeding of the unsifted ashes into the sifting member will prevent overloading of the same and greatly facilitate in separating the ash dust from the unburnt coals.

It is to be understood that the form of my invention herewith shown and described is to be taken as the preferred example of the same, and that various changes in the shape, size, and arrangement of parts may be resorted to without departing from the spirit of the invention and the scope of the subjoined claim.

Having thus described the invention, I claim:

In a device of the character described, a casing, a hopper having an opening carried by said casing, a flap valve secured to a rod pivotally supported by said hopper, a one-piece spring member coiled around said rod adjacent its opposite ends extending laterally in opposite directions to engage the under surfaces of said hopper and valve for normally retaining the latter in its closed position, a wire member secured to said rod extending transversely of said valve to be bent around the valve engaging portion of said spring member for forming a depending arm, an inclined sifting member swingingly supported within said casing, means for operating said sifting member, and a rod connecting said depending arm to said means for actuating said sifter and valve in unison.

In testimony whereof I affix my signature.

WILEM YUSKIEWICZ.
